WELL CEMENTING APPARATUS

Clarence E. Burt, Los Angeles, and William S. Althouse, Jr., South Pasadena, Calif., assignors to Baker Oil Tools, Inc., Vernon, Calif., a corporation of California

Application April 3, 1942, Serial No. 437,548

11 Claims. (Cl. 166—1)

This invention relates to well cementing apparatus adapted to form part of a casing string.

It is an object of the present invention to provide an apparatus capable of forming part of a casing string, having an internal sleeve valve of sturdy construction and improved drillable characteristics, which can be shifted to valve opening position against the resistance of frangible or similar locking devices tending to hold it in valve closing position.

A further object of the invention is to provide a well apparatus embodying a composite internal sleeve valve formed predominantly of readily drillable material and secondarily of a less readily drillable material capable of more efficient shearing of frangible means tending to prevent movement of the sleeve valve.

This invention has other objects that will become apparent from a consideration of the various forms of apparatus shown in the drawings accompanying and forming part of the present specification. These forms will now be described in detail to illustrate the general principles of the invention, but it is to be understood that such detailed description is not to be taken in a limited sense, since the scope of the invention is best described by the claims appended hereto.

Referring to the drawings:

Figure 1 is a longitudinal view, partly in section and partly in elevation, of one form of apparatus with its sleeve valve in one position;

Figure 2 is a view similar to Figure 1 with the sleeve valve in another position;

Figure 3 is a cross section taken along the line 3—3 in Figure 1;

Figure 4 is a longitudinal view, partly in section and partly in elevation, of another embodiment of the invention with its valve in one operative position;

Figure 5 is a view similar to Figure 4 with the valve in another operative position;

Figure 6 is a longitudinal view similar to Figure 1 of still another form of the invention;

Figure 7 is a longitudinal view of the apparatus in Figure 6 with the sleeve valve in another operative position;

Figure 8 is a view similar to Figure 1 of still another form of the invention; and

Figure 9 is a longitudinal view of the apparatus in Figure 8 with the sleeve valve in another operative position.

The same reference numerals refer to like parts throughout the several views and embodiments of the invention.

In its general aspects, the invention is directed

to an apparatus designed to form part of a casing string, which embodies a sleeve valve for controlling the passage of fluids through ports or openings in the apparatus. The sleeve valve is made of a readily drillable material, which is much easier to drill up than cast iron, aluminum, and similar materials heretofore used. Such more readily drillable materials as are available are incapable of efficiently rendering locking means ineffective that normally hold the sleeve valve in a particular position with respect to the ports of the apparatus, usually due to the comparatively brittle properties of the material employed. It is therefore proposed to overcome this difficulty by incorporating a different material in the sleeve valve construction designed to operate on the locking devices in concert with the comparatively brittle material to render the devices ineffective when the sleeve valve is to be shifted, as by hydraulic action. The comparatively brittle material forms the predominant part of the sleeve valve, and the less readily drillable material, such as cast iron, aluminum, etc., forms a comparatively minor part of the sleeve valve construction. As a result, after the sleeve valve has performed its desired functions in the apparatus, it can be more readily removed by a drill bit than if the entire sleeve valve were made of cast iron and similar materials.

The forms of invention disclosed in the drawings consist of a tubular collar 10 adapted to form part of a casing string by being threaded at its opposite ends to upper and lower casing sections 11, 12. This collar is provided with lateral ports or outlets 13 through which fluids may pass from the interior of the casing string into the annulus between its exterior and the wall of the bore hole. If desired, return flow of such fluids is preventable by any suitable back pressure valve device, which in the present instance consists of a flexible sleeve valve 14 of rubber or similar material whose lower end is fixed to the exterior of the collar and whose remaining upper portion is free to flex outwardly away from the ports 13 under the influence of fluids passing therethrough. Any tendency for such fluids to flow back through the ports is prevented by the rubber sleeve 14 snugly embracing the ported collar area.

The action of the flexible sleeve valve can be supplemented by a plurality of closely spaced longitudinal leaf springs 15 extending circumferentially around the flexible sleeve 14. The lower ends of these springs are welded to the collar 10 below the lower end of the flexible sleeve, and the spring portions extending upwardly from

this point of attachment to the collar extend over and engage the flexible sleeve valve 14 to add its spring action to the inherent elasticity of the flexible sleeve tending to hold it in closed position over the ports 13. It is therefore necessary for the fluid under pressure within the casing string to overcome both the elasticity of the rubber sleeve valve 14 and leaf springs 15 in opening the ports 13. Not only do the leaf springs 15 assist in the functioning of the rubber sleeve 14 as a back pressure valve, but they also serve to protect it against damage during lowering of the casing string in the well bore.

Passage of fluids through the ports 13 is controlled by a sleeve valve 16 slideable within the collar 10. This valve is initially held over the ports by frangible means, such as shear screws 17, which position its upper and lower side seals 18, 19 on opposite sides of the ports to prevent flow of fluids in either direction between the exterior of the sleeve and wall of the collar for passage outwardly through the ports 13. A tripping or bridging ball 20 introduced in the casing string can gravitate through the casing fluids until it engages a valve seat 21 in the sleeve 16 to close its central passage 22, thus enabling pressure to be built up in the casing fluid and cause it to exert a downward force on the sleeve 16 of sufficient degree to shear the screws 17 and move the sleeve 16 downwardly in the collar to a position in which the upper seal 18 is below the ports 13. Fluids may then pass outwardly through the open ports to the exterior of the casing string. The fluids must follow this direction since they are incapable of passing downwardly through the sleeve 16 by the bore closing action of the tripping ball 20. It is to be noted that downward movement of the sleeve 16 is limited by engagement of its lower end with the upper end of the lower casing section 12 (as in Figures 2, 5 and 9).

The sleeve valve 16 is of composite construction. It is made primarily of a readily drillable material, such as a phenolic casting resin, known as "Baker" casting resin or "Catalin." The sleeve valve can be cast in suitable molds to a sufficiently accurate degree permitting its use in the apparatus without the performance of any subsequent machine work. This material has the requisite strength for use as a sleeve valve, and, after the well casing has been cemented, it can be drilled up much more readily than materials heretofore used, such as cast iron or aluminum. However, the material appears to be more brittle than cast iron or aluminum, and therefore does not operate as efficiently in effecting a clean shear of the screws when they are threaded directly into the material.

The difficulty noted has been overcome in the embodiment disclosed in Figures 1, 2 and 3 by inserting a plurality of cast iron or aluminum plugs 23 at spaced points circumferentially around the sleeve and by screwing the shear pins 17 into the threaded bores of these plugs. The plugs 23 may be threaded into the resin sleeve material after drilling and tapping the latter following the molding operation, or they may be molded directly into this material. Regardless of the method of manufacture employed, the engagement of the tripping ball 20 with the seat 21 to close the sleeve bore 22 enables the hydraulic force on the ball and sleeve to be transmitted to the shear screws 17 through the agency of the cast iron or aluminum plugs 23, thus obtaining a clean fracture or shearing of the pins and al-

lowing the sleeve 16 to be moved downwardly to port opening position. The plugs 23 are of much larger size than the shear pins 17 and do not crush the comparatively brittle material of 5 which the sleeve is primarily formed.

As was described above, downward movement of the sleeve 16 is limited by its engagement with the upper end of the lower casing section 12. Its upward movement is limited by providing a 10 shoulder 24 on the sleeve engageable with a corresponding stop shoulder 25 formed in the collar 10. In addition to limiting the extent of upward movement of the sleeve 16 and preventing upwardly directed forces on the sleeve from being 15 transmitted to the shear pins 17, the engaged shoulders 24, 25 also assist in locating the plugs 23 with respect to the holes in the collar 10 through which the shear pins 17 are inserted.

The form of invention disclosed in Figures 4 20 and 5 is similar in most respects to the one just described. However, the construction is simplified through the omission of the threaded plugs 23. Instead of employing the plugs, the cast phenolic main portion of the sleeve 16 rests upon 25 a cast iron or aluminum ring 26, forming another portion of said sleeve, into which is threaded the shear screws 17, whose purpose is to position the valve seals 18, 19 on opposite sides of the ports 13. After the tripping ball 20 engages the seat 30 21, an increase in the hydraulic pressure of the fluids above the sleeve shears the screws 17 and moves the sleeve downwardly, as limited by engagement of the ring 26 with the end of the 35 lower casing section 12, in which position the collar ports 13 are open. As in the other form of invention, upward movement of the sleeve is prevented by engagement between the sleeve shoulder 24 and collar shoulder 25.

The form of invention disclosed in Figures 6 40 and 7 is similar to that shown in Figures 4 and 5. However, sometimes a shoulder cannot be provided in the collar to engage with a cooperable shoulder on the sleeve to prevent upward movement of the latter, as when the entire casing 45 string must be internally flush. Such upward movement is prevented in the Figures 6 and 7 form of invention by interlocking the sleeve 16 with the cast iron or aluminum ring 26. The cast 50 iron ring has an inturned flange 27 forming an internal circumferential groove in which is received an external flange 28 at the lower end of the phenolic portion of the sleeve, thus forming an interlocking fit. The ring portion 26, 27 of 55 the sleeve and phenolic cast portion of the sleeve may be secured together by inserting the ring in the mold and casting the remainder of the sleeve thereto.

Inasmuch as the entire casing string is internally flush, downward movement of the sleeve 16 by hydraulic action after shearing of the screws 17 is limited by an inwardly extending, drillable stop ring 29 secured at any suitable point below the sleeve, as by positioning it between the collar 10 and lower casing section 12.

The form of invention shown in Figures 8 and 9 is also similar to Figures 4 and 5. However, other features have been added, such as providing a back pressure valve in the slideable sleeve valve 16, which allows the casing string to be floated in the well bore, and also prevents fluids from below the sleeve from passing upwardly through it. This back pressure valve consists of a ball 30, preferably buoyant in cement slurry, movable upwardly to engage a seat 31 in the

sleeve valve 16 to close its bore 22 against upward passage of fluids. Downward movement of the ball 30 is limited by its engagement with a spaced stop fingers 32 extending inwardly from a ball stop ring 33 positioned between the cast iron shear ring 26 and the remaining phenolic portion of the sleeve 16. This ring 33 and its fingers 32 are formed integrally from the same material as the upper portion of the sleeve, but is made as a separate unit to permit insertion of the ball 30 within the sleeve 16.

Instead of limiting upward movement of the sleeve by the engagement of an external phenolic resin shoulder with an internal shoulder in the collar, as in the Figures 4 and 5 embodiment, the greater loads imposed on the sleeve 16 due to its supporting the casing string while the latter is being run in the well bore require the use of a cast iron or aluminum stop ring 34 molded into the resin portion of the sleeve and engageable with the collar shoulder 25. Stop rings 34 made of this material have a greater crushing strength than the phenolic material from which the sleeve 16 and ball stop ring 33 are made.

After engagement of the tripping ball 20 with the upper seat 21 in the sleeve valve, pressure built up in the fluids thereabove shears the screws 11 and shifts the entire internal construction downwardly to a position limited by engagement of the cast iron or aluminum shear ring 26 with a lower casing section 12. Fluids may then be displaced through the collar ports 13. Were there any tendency for fluids to pass upwardly into the casing below the sleeve valve, the back pressure ball 30 would engage its seat 31 to prevent such passage, and if the upwardly directed fluid forces were great enough, the back pressure ball 30 and the upper sleeve valve body would then be moved upwardly until the stop ring 34 engages the collar shoulder 25, preventing further movement from occurring. As a result of this upward return movement of the sleeve valve 16, it would again be positioned over the ports 13 and assist the flexible sleeve valve 14 on the exterior of the collar 10 in preventing return passage of fluids through the ports 13 into the casing string.

In all forms of the invention, after cement or slurry has been ejected through the ports 13 and has set and hardened, a suitable drill bit can be run in the casing and the internal valve mechanism drilled out. This can be done very readily in view of the relative predominance of the phenolic casting material from which most of the sleeve valve 16 is made. The cast iron or aluminum parts of the sleeve valve construction are also readily drillable, but not as easily as the remainder of the sleeve valve. As a result, the entire portion within the collar is removable much easier and in much less time than would be the case were it to be made entirely of cast iron or similar materials.

We claim:

1. Apparatus of the character described, including a tubular member having ports adapted to form part of a casing string, a sleeve valve within said member for controlling passage of fluids through said ports, said sleeve valve being made of readily drillable material and having circumferentially spaced inserts in said material of less readily drillable material, and frangible means extending into said member and inserts for holding said sleeve valve in position closing said ports, said first-mentioned readily drillable material having such characteristics as to be incapable alone of effectively disrupting said frangible

means upon imposing sufficient force on said valve.

2. Apparatus of the character described, including a tubular member having ports adapted to form part of a casing string, a sleeve valve within said member for controlling passage of fluids through said ports, said sleeve valve being made of readily drillable material, and also of a ring of less readily drillable material, and releasable means on said member cooperable with said ring for holding said sleeve valve in a fixed position with respect to said ports, said first-mentioned readily drillable material having such characteristics as to be incapable alone of releasing said means upon subjecting said valve to pressure.

3. Apparatus of the character described, including a tubular member having ports adapted to form part of a casing string, a sleeve valve within said member for controlling passage of fluids through said ports, said sleeve valve being made predominantly of readily drillable material and secondarily of less readily drillable material, frangible means connected to said tubular member and less readily drillable material for holding said sleeve valve over said ports, said predominantly readily drillable material having such characteristics as to be incapable alone of effectively disrupting said frangible means upon imposing sufficient force on said valve, and cooperative means on said sleeve valve and member for limiting the extent of movement of said sleeve valve within said member in one direction.

4. Apparatus of the character described, including a tubular member having ports adapted to form part of a casing string, a sleeve valve within said member for controlling passage of fluids through said ports, said sleeve valve being made of readily drillable material and also of a ring of less readily drillable material, and frangible means extending into said member and ring for holding said sleeve valve in a position closing said ports, said first-mentioned readily drillable material having such characteristics as to be incapable alone of effectively disrupting said frangible means upon imposing sufficient force on said valve.

5. Apparatus of the character described, including a tubular member having ports adapted to form part of a casing string, a sleeve valve slidable within said member for controlling passage of fluids through said ports, said sleeve valve being made of readily drillable material and also of a ring at the lower end of such material of less readily drillable material, and frangible means extending into said member and ring for holding said sleeve valve in a position closing said ports, said first-mentioned readily drillable material having such characteristics as to be incapable alone of effectively disrupting said frangible means upon imposing sufficient force on said valve.

6. Apparatus of the character described, including a tubular member having ports adapted to form part of a casing string, a sleeve valve slidable within said member for controlling passage of fluids through said ports, said sleeve valve being made of readily drillable material and also of a ring at the lower end of such material of less readily drillable material, frangible means extending into said member and ring for holding said sleeve valve in a position closing said ports, said first-mentioned readily drillable material having such characteristics as to be incapable alone of effectively disrupting said frangible

gible means upon imposing sufficient force on said valve, and means on said sleeve valve engageable with said member for limiting movement of said sleeve valve within said member in an upward direction.

7. Apparatus of the character described, including a tubular member having ports adapted to form part of a casing string, a sleeve valve slideable within said member for controlling passage of fluids through said ports, said sleeve valve being made predominantly of readily drillable material and secondarily of less readily drillable material, frangible means connected to said tubular member and less readily drillable material for holding said sleeve valve over said ports, said predominantly readily drillable material having such characteristics as to be incapable alone of effectively disrupting said frangible means upon imposing sufficient force on said valve, cooperative means on said sleeve valve and member for limiting the extent of upward movement of said sleeve valve within said member, and back pressure valve means movable upwardly against said sleeve valve to close a central passage therethrough.

8. Apparatus of the character described, including a tubular member having ports adapted to form part of a casing string, a sleeve valve within said member for controlling passage of fluids through said ports, said sleeve valve being made of readily drillable material and also of a ring at the lower end of such material of less readily drillable material, frangible means extending into said member and ring for holding said sleeve valve in a position closing said ports, said first-mentioned readily drillable material having such characteristics as to be incapable alone of effectively disrupting said frangible means upon imposing sufficient force on said valve, means on said sleeve valve engageable with said member for limiting upward movement of said sleeve valve within said member, and back pressure valve means movable upwardly against

said sleeve valve to close a central passage therethrough.

9. Apparatus of the character described, including a tubular member having ports adapted to form part of a casing string, a sleeve valve within said member for controlling passage of fluids through said ports, and releasable means for holding said sleeve valve in a fixed position with respect to said ports, said sleeve valve comprising predominantly readily drillable material of such characteristics as to be incapable alone of effectively releasing said means upon subjecting said valve to pressure and secondarily of less readily drillable material engaging said means and operative to release said means when said valve is subjected to sufficient pressure.

10. Apparatus of the character described, including a tubular member having ports adapted to form part of a casing string, a slideable sleeve valve within said member for controlling passage of fluid through said ports, and frangible means for holding said sleeve valve over said ports, said sleeve valve being composed predominantly of readily drillable material of such characteristics as to be incapable alone of effectively disrupting said frangible means upon imposing a longitudinal force on said valve and secondarily of less readily drillable material connected to said frangible means to effect disruption of the latter upon longitudinal movement of said sleeve valve.

11. Apparatus of the character described, including a tubular member having ports adapted to form part of a casing string, a sleeve valve within said member for controlling passage of fluids through said ports, said sleeve valve being made predominantly of a comparatively brittle synthetic resin, and secondarily of a material that is less brittle than said resin, and frangible means connected to said tubular member and less brittle material for initially holding said sleeve valve over said ports.
